UNITED STATES PATENT OFFICE.

JAMES WILBURN AND JORDAN J. JEFFERSON, OF KINGSVILLE, TEXAS.

RERAILING DEVICE.

Application filed March 13, 1926. Serial No. 94,519.

This invention relates to improvements in car rerailing devices and has for an object the provision of a device which may be used upon either the right or left hand rail of a track and thus obviate the necessity of providing right and left hand devices and save the time and labor frequently required in adjusting the device to the proper rail.

Another object of the invention is the provision of a device of the above character which is relatively light, strong and durable in construction, and will provide proper firm contacting engagement with the ties or roadbed, without contact with spikes or rail plates, and thus eliminate danger of rocking or turning over, when the device is in use.

Another object of the invention is the provision of means for insuring proper position of the car wheels upon the rails as the wheels leave the rerailing device.

With the above and other objects in view, the invention further includes the following novel features and details of construction, to be hereinafter more fully described, illustrated in the accompanying drawings and pointed out in the appended claim.

In the drawings:

Figure 1 is a plan view showing the invention in position for use.

Figure 2 is a section on the line 2—2 of Figure 1.

Figure 3 is an enlarged section on the line 3—3 of Figure 2.

Figure 4 is an enlarged section on the line 4—4 of Figure 2.

Referring to the drawings in detail wherein like characters of reference denote corresponding parts, the device as illustrated comprises a body having a substantially central longitudinally disposed portion 10 and oppositely inclined ends 11. The portion 10 is provided with a longitudinally disposed rail receiving slot 12 which opens at the inclined ends 11 and is designed to receive a rail 13.

Spaced upon opposite sides of the portion 10 are vertically inclined longitudinally disposed walls 14, the said walls being connected to the portion 10 by spaced webs or ribs 15. The lower edges of these ribs terminate short of the lower edges of the walls 14 for the accommodation of the rail spikes or rail plates. The device may thus have a firm contacting engagement with the ties or roadbed so that danger of tilting will be prevented. The walls 14 are provided with openings 16 to

reduce weight and with additional openings 17 near opposite ends thereof for convenience in handling.

The opposite upper side edges of the device are provided with relatively inclined flanges 18. The lower outer ends of these flanges are spaced laterally from the side edges of the slot 12 so as to provide wheel receiving inclines 19 at either side of the slot, or at either side of the rail as shown in Figure 1 of the drawings. The device may thus be used upon either a right or left hand rail. The ribs or flanges 18 incline inwardly and provide a substantially central restricted guide channel 20. Located beyond the opposite ends of this channel upon the inclined portions 11 are longitudinally disposed guide ribs 21. These ribs are spaced from the slot 12 and act to engage the wheel flanges and guide the wheel upon the rail.

A horizontally disposed flange or rib 22 extends laterally from one side edge of the device.

The invention is susceptible of various changes in its form, proportions and minor details of construction and the right is herein reserved to make such changes as properly fall within the scope of the appended claim.

Having described the invention what is claimed is:

A car rerailing device comprising a body having oppositely inclined ends, a substantially central longitudinally disposed portion extending throughout the length of the body and having a rail receiving slot therein to engage over the head of a rail, vertically inclined side walls spaced outwardly from opposite sides of the central portion, transverse webs connecting the side walls and central portion, with the lower edges of the webs spaced upwardly from the lower edges of the side walls to accommodate the rail base flanges and oppositely inclined guide flanges extending along opposite side edges of the body, said flanges having their outer lower ends spaced laterally from the opposite side edges of the longitudinal slot and inclining upwardly and inwardly to provide a restricted guide channel substantially central of the width of the body.

In testimony whereof we affix our signatures.

JORDAN J. JEFFERSON.
JAMES WILBURN.
